UNITED STATES PATENT OFFICE.

CHARLES H. KIMBALL, OF CHICAGO, ILLINOIS.

DESIGN FOR A HEAD OR FOOT PIECE FOR METAL BEDS.

SPECIFICATION forming part of Design No. 29,552, dated October 25, 1898.

Application filed July 5, 1898. Serial No. 685,175. Term of patent 3½ years.

To all whom it may concern:

Be it known that I, CHARLES H. KIMBALL, of Chicago, in the county of Cook and State of Illinois, have invented a new and original 5 Design for a Head or Foot Piece for Metal Beds, of which the following is a specification.

My novel design consists in the head or foot piece for metal beds having as its characteristic feature the peculiar pattern or configuration of scrollwork constituting the upper panel or trimming of the head or foot piece, as illustrated in the accompanying drawings, in which—

Figure 1 is a front elevation of a head or foot piece embodying my novel design. Fig. 15 2 is a vertical section thereof, taken on line 2 2 of Fig. 1.

Those parts of the head or foot pieces in the shape and configuration of which the novelty 20 of my design resides are represented in the drawings in full lines.

Between the corner-posts A and above the main framework B are two double scrolls C and D, both bent convexly upward and arranged symmetrically about a center post E. 25 The outer scroll C is of wider curve and extends substantially the full distance between the posts A, inclosing the inner scroll D, and the two scrolls are in contact at the upper end of the center post E, as shown. 30

I claim as my invention—

The design for the head or foot piece for metal beds, substantially as shown and described.

In testimony that I claim the foregoing as 35 my invention I affix my signature hereto, in the presence of two subscribing witnesses, this 29th day of June, A. D. 1898.

CHARLES H. KIMBALL.
